UNITED STATES PATENT OFFICE.

FREDERICK HODSCHAR, OF BROOKLYN, NEW YORK.

WET-CLEANING ATTACHMENT FOR CARPET-SWEEPERS.

1,221,324.

Specification of Letters Patent.

Patented Apr. 3, 1917.

Application filed January 9, 1915. Serial No. 1,289.

To all whom it may concern:

Be it known that I, FREDERICK HODSCHAR, a subject of the Emperor of Austria-Hungary, and a resident of New York, borough of Brooklyn, in the county of Kings and State of New York, have invented certain new and useful Improvements in Wet-Cleaning Attachments for Carpet-Sweepers, of which the following is a specification.

10 This invention relates to carpet sweeping apparatus and has particularly in view to provide an attachment to a brush or carpet sweeper whereby the carpet may be renovated by a liquid during the brushing or 15 sweeping operation.

In carrying out my invention, I provide an attachment comprising a distributing device which automatically feeds from a fountain the required amount of liquid and 20 applies it upon the carpet preferably in advance of the brushing or sweeping element. Thus, a liquid may be used such as ammonia or the like which has the effect of giving a luster and renovated appearance to the 25 carpet. Also, if desired, a disinfectant may be applied in the liquid for disinfecting the carpet as well as cleaning and improving its appearance.

20 In the drawings illustrating the preferred embodiments of this invention,

Figure 1 is a plan view and Fig. 2 is a side elevational view of my improved attachment applied to a brush.

Fig. 3 is a fragmental view in continuation of Fig. 2 illustrating the adjustment whereby the attachment may be lifted out of contact with the carpet.

Fig. 4 is a fragmental view illustrating the position of the roller and fountain when 40 so lifted.

Fig. 5 is a bottom plan view of the fountain and roller, part of the roller being broken away to illustrate the feed holes.

Fig. 6 is a side elevation and Fig. 7 is a plan view of the invention shown as applied to the rotary type of carpet sweeper.

Referring in detail to the drawings, particularly to Figs. 1 to 5, the attachment is shown as applied to a brush 10, having the 50 usual handle 11. The attachment proper consists of a fountain 12 of any suitable shape provided at the bottom thereof preferably with very fine openings 13 which normally retain the liquid by capillary attraction. Rotatably mounted adjacent to these feed openings is a distributing roller

14 having a surface formed of some absorbent material which will absorb the liquid through the feed openings 13 and distribute the same upon the carpet. The roller is 60 preferably journaled in a pair of ears 15 extending from the ends of the fountain. These ears are formed with slots 16 through which extend the pintles 17 of the roller. Thus, when the fountain is dropped to bring 65 the roller in contact with the carpet, the bottom side of the fountain with the feed openings drops into contact with the roller. As soon, however, as it is desired to dispense with the use of the liquid, the fountain may 70 be lifted and the roller thus drops out of contact with the feed openings and interrupts the flow of the liquid (Fig. 4), inasmuch as the holes as before stated are so small that the liquid is retained by capillary 75 action. The fountain is movably mounted upon the brush by means of hooks 18 extending from each end thereof engaging eyes or staples 19 secured to the brush. These hooks form a pivotal joint with the 80 eyes 19 and thus a chain 20 attached to the fountain as by means of an eye 21 formed thereon may be pulled and adjusted upon one of a number of hooks 22-22^a attached to the handle 11. 85

When it is desired to dispense with the use of the liquid, the chain 20 is merely pulled and adjusted upon a higher hook 22^a, thus lifting the fountain and roller out of contact with the carpet and freeing the feed openings from the absorbent action of the roller 14 as the roller drops in the slot 16 (Fig. 4). For strengthening the fountain, reinforcing bands or bars 23 may be formed about the ends of the fountain. These bars 90 preferably constitute a continuation of the hooks 18. Also a longitudinal strengthening bar 24 may be attached to the front of the fountain to take up shock of impact in hitting furniture as sometimes happens during the course of sweeping. 95

For refilling the fountain, an opening is provided preferably on the underside adjacent to the feed openings, this filling opening being closed by a cap 25. Thus, when out of use, the fountain may be unhooked from the staples and turned upside-down and rested upon the side having the hook bars 18. The latter and the eye 21 will prevent the cylindrical receptacle from overturning. In this inverted position, the feed roller drops down upon the feed apertures 100

105

110

and closes the same, thus preventing evaporation of the liquid.

To prevent the feed roller from slinging liquid in the direction of the brush, I provide a guard 26 attached to the fountain casing at the rear of the feed roller. No provision need be made for the slinging of the liquid to the front as this will merely fall on the carpet to be gone over by the brush and will not be detrimental.

In Figs. 6 and 7, I have illustrated my improved attachment as applied to a rotary carpet sweeper of the usual well known type. This rotary form of sweeper comprises a casing 30 having the usual ground wheels 31 and handle 32. The fountain is pivoted to the staples as in the previous form described, but the hooked arms 18 instead of extending longitudinally of the reinforcing bars 23 are formed with offsets 18^a for the purpose of clearing the operating bars 33 extending out from the forward portion of the casing of the carpet sweeper. Otherwise, the construction and mode of operation is similar to that described in reference to Figs. 1 to 5.

It will thus be seen that I have provided an attachment which can be readily hooked onto a carpet brush or rotary carpet sweeper without altering the construction of the latter and provides for renovating the carpet simultaneously with the sweeping or brushing operation. Also the attachment may be readily removed from the sweeper by a simple operation consisting merely in swinging the fountain upward sufficiently to allow the hooks to disengage from the staples. The attachment may be manufactured at very small cost and is easily applied to the carpet brushing or sweeping apparatus now in use.

Having thus described my invention, I claim as new and desire to secure by Letters Patent:

1. An attachment for carpet sweepers comprising a fountain having means for connecting the same with the sweeper, said fountain being provided at the bottom thereof with small feed apertures, and a feed roller mounted adjacent said feed apertures and movable toward and away therefrom.

2. An attachment for carpet sweepers consisting of a fountain formed with feed apertures in the bottom thereof, ears having slots disposed at the ends of the fountain, and a feed roller journaled in said slots adapted to contact with the fountain at said apertures.

3. An attachment for carpet sweepers comprising a fountain having feed apertures, a feed roller mounted thereon adjacent to the feed apertures, hooks extending from the fountain, and a chain attached thereto for lifting the same out of operative relation with the carpet.

4. An attachment for carpet sweepers comprising a fountain having feed apertures, a roller mounted adjacent said feed apertures, a guard for preventing the sling- 70 ing of liquid from the roller, and hooks extending from the fountain adapted to detachably hook the fountain to a sweeper.

5. An attachment for carpet sweepers comprising a fountain having minute feed apertures at the bottom thereof, a feeding element mounted adjacent said apertures and movable to and from said apertures to come into and out of wiping engagement therewith, said fountain being provided with a filling aperture located adjacent said feed apertures.

6. An attachment for carpet sweepers comprising a fountain having feed apertures disposed at the bottom thereof, these apertures being so minute that the capillary 85 action will normally prevent the escape of the liquid, and a movable feed element disposed adjacent said apertures adapted to remove the liquid in small quantities and apply the same to the carpet, said feed element being movable into contact with the liquid at the feed apertures during the operation of the device and movable away from the feed apertures when the device is not in operation.

Signed at New York city, in the county of New York, and State of New York, this 7th day of January, A. D. 1915.

FREDERICK HODSCHAR.
